James K. Balzhiser, Cuyahoga Falls, Ohio, assignor to
The B. F. Goodrich Company, New York, N. Y., a corporation of New York

Application July 26, 1954, Serial No. 31,598

Term of patent 14 years

(Cl. D90—20)

To all whom it may concern:

Be it known that I, James K. Balzhiser, a citizen of the United States of America, residing at Cuyahoga Falls, in the county of Summit and State of Ohio, have invented a new, original, and ornamental Design for a Tire, of which the following is a specification, reference being had to the accompanying drawings, forming a part thereof.

In the drawings:

Fig. 1 is a perspective view of a tire showing my new design;

Fig. 2 is a fragmentary view thereof drawn to an enlarged scale; and

Fig. 3 is an enlarged sectional view taken on line 3—3 of Fig. 1.

The dotted line disclosure in Fig. 1 is understood to represent the repetition of the design shown in full lines.

I claim:

The ornamental design for a tire, as shown and described.
